UNITED STATES PATENT OFFICE.

ELLIS F. EDGAR, OF WOODBRIDGE, NEW JERSEY.

STEAM-BOILER.

No. 798,997.

Specification of Letters Patent.

Patented Sept. 5, 1905.

Application filed November 21, 1901. Serial No. 83,199.

To all whom it may concern:

Be it known that I, ELLIS F. EDGAR, a citizen of the United States, and a resident of Woodbridge, in the county of Middlesex and 5 State of New Jersey, have invented certain new and useful Improvements in Steam-Boilers, of which the following is a specification.

Figure 1 is a one end or one front outside vertical view of a boiler embodying my improvements without the superheating attachment. Fig. 2 is a vertical section view through the center of the furnace at lines 2 2 on Fig. 1. Fig. 3 is a sectional plan view at lines 3 3 on Fig. 1 with part of the grate-bars removed. Fig. 4 is a sectional plan view of one section with a half of furnace on each side. Fig. 5 is an end elevation view of one section with casing removed. Fig. 6 is a detached enlarged view of upper support for 10 side casings secured to upper drum 2. Fig. 7 is a detached enlarged view of lower support for side casing secured to lower drum 1. Fig. 8 is a plan view, partially in section and partially in full, of my superheating attachment. Fig. 9 is a vertical end view, partially in full and partially in section, broken away at lines 1 1 in Fig. 8 to show my superheating attachment. Fig. 10 is a vertical side elevation view of a boiler-section with draft- 15 exit at each end.

My invention relates more particularly to a vertical water-tube boiler usually of four drums or more and, where desired, a superheating attachment attached between the last 20 outside row of water-tubes and the outside casing, substantially as shown in Figs. 8 and 9. There is one upper drum 2 and one lower drum 1 in a section. These drums are connected by water-tubes 14. An important feature of this boiler is a long open furnace extending the length of the boiler and fired at each end of the boiler forming a large combustion-chamber, with a brick-lined casing at each end with special bricks 5, and brick arch 25 forming the top of the furnace with bricks 3 and upper bricks 4, and the grate of the furnace preferably extending the entire length of the furnace and preferably divided in the center and preferably of a shaking type operated at each end of the furnace, and the boiler-sections composed of one upper drum 2 and lower drum 1, connected by water-tubes 14 on each side of said furnace. Most of the 30 water-tubes are exposed to the direct radiation of the heat from the furnace. Part of the tubes are cut off from the direct radiation

of the heat from the furnace by wall 12, supported on lugs 19, held in position by water-tubes 13. Usually the draft-exits are at one end of the boiler, the same end as wall 12, although the boiler at the same time is fired from both ends, as shown in Fig. 2, having fire-doors 22 at each end of the furnace. This boiler may be called a "double-end-fired" or "double-front" boiler.

In some cases I may construct draft at both ends of the boiler, as shown in Fig. 4 and Fig. 10. In this case the heat is deflected on the majority of the tubes through the center of the section, the tubes at each end being cut 40 off from the heat of the furnace by walls 12, as shown in Fig. 4 and Fig. 10. I show a section in Fig. 4 with half of a furnace on each side of said section. This construction would be more applicable to large boilers 45 containing more than two sections and more than one furnace—may be three sections and two furnaces or four sections and three furnaces. Fig. 10 shows a vertical side elevation of a boiler-section embodying features of construction set forth in this case—upper drum 2, lower drum 1, connected by tubes 14, draft-exit at each end 11, baffle-walls at each end 12, steam-exit 15, blow-off 16, grate 7, extending length of furnace, bearing-bars 17, 50 supporting grate 7. In this view I do not show upper back arch 3 between upper drums 2, only showing here lower brick arches 3 between drums 1. These lower arches vary in construction and position according to 55 whether the boiler is to be constructed to fire at one end or both ends. In this view it is shown for a construction to be fired at both ends of the furnace. The object of these lower brick arches is to prevent the refrigerating effect from the heating-surface on the fire-bed, which retards combustion, and in a case of firing with bituminous coal these arches will prevent smoke. The gases after 60 passing from under these lower arches enter 65 into the larger secondary field of combustion, which takes place in the large combustion-chamber between these arches and the upper arch supported by upper drum 2. The gases from the furnace after entering between tubes 70 14 pass between baffle-walls 12, located on each side of the bank of tubes 14 at the draft-exit end or ends, then the gases pass into gas 75 exit or uptake 11, thence to the chimney. In Fig. 5 I show one end of one of these sections, 80 showing how the tubes are put in and how the side casings are supported, Fig. 7 show-

ing a detached enlarged view of lower support for side casing secured to lower drum 1, bracket 26 being riveted to lower drum 1, base-plate 27, upon which rests the cast-iron casing 6, and special fire-brick lining 5, containing dead-air space 24. Asbestos felt 23 is also shown, which forms a lining between cast-iron 6 and special bricks 5.

Fig. 6 shows an enlarged detached view of upper support for side casing, bracket 29 being riveted to upper drum 2. Angle-iron plate 28 being bolted to bracket 29 holds cast-iron casing 6 in position and extends down far enough over casing 6 so as to hold said casing in position when the upper drum 2 is forced up by expanding of water-tubes 14 upon being heated, and as they contract by cooling this plate 28 slides back in former position, always keeping cast-iron plate 6 in proper position. Asbestos loop packing 25 is to form a cushion and make a tight joint during the expanding and contracting of water-tubes 14.

Up to five-hundred-horse power I would usually build this boiler with one furnace and one section on each side of furnace, as shown in Fig. 3, showing one section on one side of the furnace—only half of the furnace, not having room on the sheet to show more on a scale to be clear.

My superheating device, a plan view of which is shown in Fig. 8, consists of receiving-pipe 30 and discharge-pipe 32, connected by superheating-pipes 31. Receiving-pipe 30 is connected to steam-exit 15 by pipe 36. The flow of steam from receiving-pipe 30 into superheating-pipes 31 is regulated by valves 35, thereby regulating the temperature to be desired by letting the steam in as many of the superheating-pipes as desired or of any velocity desired, thereby absolutely controlling the degree of superheat desired into discharge-pipe 32. Valves 34 next to discharge-pipe 32 are to be used in case of accident and a new superheating-pipe 31 necessary to be installed while the boiler is in operation, or where only part of superheating-pipes 31 are desired to be in use valves 34 may be closed to prevent back pressure into pipes 31 not being used.

The advantages to be derived by a large furnace, as shown in Fig. 2, will readily be seen by one familiar with combustion—the possibility of obtaining perfect combustion

by proper firing. This can readily be done 55 with this boiler, as it is fired at each end, and having two fire-doors at each end it can be fired one-quarter of the grate at a time, thereby maintaining steam-pressure and obtaining perfect combustion, and in clearing fires with 60 small anthracite coal by clearing one-quarter of the fire at a time will not lower the steam-pressure, thereby depreciating the horse-power, which is a very important factor in a 65 steam plant.

Having thus described my invention, what I claim as new, and desire to secure by Letters Patent, is—

1. In a vertical water-tube boiler one or more oblong sections composed of one drum 70 above another connected by water-tubes having a draft-exit at each end of the section.

2. In a vertical water-tube boiler one or more oblong sections composed of one drum above another connected by water-tubes 75 having a draft-exit at each end of the section, a furnace on each side of each section.

3. In a vertical water-tube boiler one or more oblong sections composed of one drum 80 above another connected by water-tubes, having a draft-exit at each end of the section, a furnace on each side of each section, and a wall extending from the draft-exit ends part of the way toward the center of the section.

4. In a vertical water-tube boiler one or 85 more oblong sections composed of one drum above another connected by water-tubes having a draft-exit at each end of the section, a furnace on each side of the section, a wall on each side of the section extending from the 90 draft-exit end part of the way toward the center of the section.

5. In a vertical water-tube boiler one or more oblong sections composed of one drum 95 above another connected by water-tubes having a draft-exit at each end of the section, a wall extending from the draft-exit end part of the way toward the center of the section all substantially as shown and described and for the purpose set forth.

Signed at New York, in the county of New York and State of New York, this 14th day of November, A. D. 1901.

ELLIS F. EDGAR.
